UNITED STATES PATENT OFFICE.

HUDSON W. HAKES, OF MILLBURY, MASSACHUSETTS.

SELF-THREADING SHUTTLE.

1,221,048.

Specification of Letters Patent.

Patented Apr. 3, 1917.

Application filed October 12, 1912. Serial No. 725,389.

To all whom it may concern:

Be it known that I, HUDSON W. HAKES, a citizen of the United States, residing at Millbury, in the county of Worcester and 5 Commonwealth of Massachusetts, have invented a new and useful Improvement in Self-Threading Shuttles, of which the following description, accompanied by drawings, is a specification.

10 My invention relates to that class of shuttles for looms wherein the filling thread is drawn by the hand of the weaver into the delivery eye of the shuttle, and my invention relates particularly to a metallic thread 15 guide adapted to be inserted in the body portion of the shuttle, having an opening therethrough which constitutes the delivery eye of the shuttle and communicates through a slit with the bobbin chamber, whereby the 20 operator can draw the filling thread from the bobbin through the slit and through a peculiarly shaped passage in the thread guide into the interior of the thread guide.

The object of my invention is to improve 25 the construction of the thread guide by which the entrance of the filling thread is facilitated and its accidental removal from the thread guide prevented, and also, further, to provide a thread guide adapted to 30 different shuttles having the communicating slit between the delivery eye and the bobbin chamber in different positions.

In the accompanying drawings,

Figure 1 is a plan view of a shuttle containing a thread guide embodying my present invention.

Fig. 2 is a side view of the forward end 40 of the shuttle, showing the position of the thread guide on the contact side of the shuttle, or the side opposite the delivery eye.

Fig. 3 is a side view of the forward end 45 of the shuttle, showing the side containing the delivery eye.

Fig. 4 is a plan view of the thread guide 50 on an enlarged scale.

Fig. 5 is a side view.

Fig. 6 is a bottom view, and

Fig. 7 is a perspective view representing 55 the position of the thread guide in the body of the shuttle, which is indicated by broken lines.

Similar reference characters refer to similar parts in the different figures.

The thread guide which embodies my 55 present invention is adapted to be used with any of the ordinary types or usual forms of

loom shuttles, having a shuttle body 1 containing a bobbin chamber 2 in which a bobbin 3 may be supported upon the bobbin spindle 4 in the usual manner. At one end 60 of the bobbin chamber 2 and in axial alignment therewith is a longitudinal recess 5 communicating at its forward end with a transverse passage 6 through the body of the shuttle substantially circular in cross 65 section. The passage 6 receives a hollow or tubular thread guide 7 provided with a thread entering slit of peculiar shape, as hereinafter described, through which the thread is allowed to enter into the interior 70 or tubular passage 8 of the thread guide.

The thread guide in the illustrated embodiment of my invention is preferably constructed from a sheet metal blank, which is pressed or rolled into substantially tubular 75 form, as represented on an enlarged scale at 7, Figs. 4 to 7 inclusive. The blank from which the thread guide is constructed is of suitable outline to form, when pressed into tubular shape, a thread guide having a 80 central passage or bore open at both ends of the guide. The end 9 of the guide is of cylindrical shape and is provided with a projecting rib 10, and the transverse passage 6 is cut away at 11 for a short distance 85 from the back side of the shuttle to admit the rib 10 and hold the thread guide from rotation in the body of the shuttle. The thread guide is positioned in the body of 90 the shuttle, as shown in Figs. 2, 3 and 7, 95 with the rib 10 on the under side of the guide. The thread guide is cut away to form a notch 12 which is exposed within the recess 5 and across which a thread 13 is drawn into a vertical arc-shaped slit 14. 95 The slit 14 communicates at one end with the recess 5 at one corner thereof, and the bottom of the arc-shaped slit 14 communicates with a slit 15, Fig. 3, leading from the slit 14 to the transverse passage 6. 100

When the thread is conducted through the recess 5 and slits 14 and 15, it will be drawn around the edge of the thread guide at the notch 12 against the outer surface 16 of a prong 17. The transverse passage 6 is cut away opposite the prong 17 to form a passage 18, to allow the thread to be drawn downward over the surface 16 of the prong 17 until it strikes an edge 19 of an opposing prong 20. With the exertion of a pull in a 110 substantially horizontal direction toward the bobbin chamber of the shuttle, the tension

upon the thread 13 causes it to move up the inclined edge 19 of the prong 20 until it is carried past the point of the prong 17 and into a slit 21 formed obliquely to the axial line of the thread guide. The thread then passes through the slit 21 into the interior passage or bore of the thread guide.

Between the passage 12 and the cylindrical end 9 of the thread guide, the guide is cut away to form a straight edge or supporting wall 22, for the purpose of adapting the thread guide for use in shuttles in which the arc-shaped guide slit 14 is changed into the position indicated by the broken lines 23, in which the slit communicates with the recess 5 upon the opposite side of the recess, causing the thread, as it is drawn into the arc-shaped slit, to lie across the edge 22 and be supported thereon while the thread is being drawn against the outer side 16 of the prong 17. At this point in threading the shuttle, the thread will be drawn laterally off the edge 22 into the notch 12.

When the thread guide is inserted in the shuttle, the delivery end 24 is brought substantially flush with the vertical outer side of the shuttle and, in this position, the widened outer end of the slit 21 leaves the shuttle wood exposed at the point 25, Fig. 7, forming a shoulder against which the thread contacts when it is drawn downward. This shoulder prevents the thread from being drawn over a rounded edge 26 of the prong 20 into the oblique slit 21. This construction prevents the accidental escape of the thread from the tubular thread passage or bore of the thread guide. In order to dis-

engage the thread from the thread guide through the slit 21, it is necessary that the thread be drawn into a position which is oblique to the axial line of the thread guide. ⁴⁰

As I have heretofore mentioned, my improved thread guide is adapted for use with shuttles having the thread passage in the body of the shuttle in different positions. ⁴⁵ If the thread passage is located as shown by the broken lines 27, Fig. 1, the thread will contact with the edge 28 of the thread guide as the thread is drawn forward. The edge 28 will then serve as a cam surface to move the thread back into the notch 12, a clearance ⁵⁰ having been provided in the body of the shuttle for that purpose.

I claim,

The combination with a loom shuttle providing a recess in alignment with its bobbin chamber, of a tubular thread guide disposed transversely to said recess, and having its wall cut away intermediate its ends for connecting said interior with said recess, with a ⁵⁵ thread entering slit extending from said cut away portion to the end of said guide, said slit having oppositely inclined portions at the bottom of the guide whereby to form a ⁶⁰ thread lock, the outer inclined portion being formed between two projecting prongs, one of which presents a convex edge extending past the vertical plane of the axis of said guide. ⁶⁵

HUDSON W. HAKES.
